UNITED STATES PATENT OFFICE

102,637

DESIGN FOR A TOBACCO PIPE

Lyndon C. Millsap, Sullivan, Ill.

Application May 1, 1936, Serial No. 62,412

Term of patent 7 years

To all whom it may concern:

Be it known that I, Lyndon C. Millsap, a citizen of the United States and a resident of Sullivan, in the county of Moultrie and State of Illinois, have invented a new, original, and ornamental Design for a Tobacco Pipe, of which the following is a specification, reference being had to the accompanying drawing, forming part thereof.

I claim:—

The ornamental design for a tobacco pipe as shown.

LYNDON C. MILLSAP.
